W. T. GODDARD

INSULATOR

Filed Oct. 1, 1921

INVENTOR

BY *Walter T. Goddard*
Frank Meekins
his ATTORNEY

UNITED STATES PATENT OFFICE.

WALTER T. GODDARD, OF HAMILTON, ONTARIO, CANADA, ASSIGNOR TO LOCKE INSULATOR CORPORATION, OF BALTIMORE, MARYLAND, A CORPORATION OF MARYLAND.

INSULATOR.

Application filed October 1, 1921. Serial No. 504,667.

The invention relates to high tension insulators, and more particularly to novel means for connecting the adjacent sections of a post insulator.

5 The primary object of my invention, broadly stated, is to provide a post insulator formed of a plurality of similar sections, the sections being adapted to be connected by metallic elements which are arranged in 10 such a manner as to equalize the strain upon the insulator and at the same time to permit free expansion and contraction of parts of the insulator under temperature changes without detriment to the insulator or to the 15 connecting mechanism.

A further object of the invention is to provide simple and effective means for securing insulating sections together, said means being located in such a manner as to 20 rigidly unite each section to the adjacent sections without projecting beyond the face or surface of the insulator.

A still further object of the invention is to provide novel means for connecting the 25 adjacent sections of a post insulator, said means being so positioned as to permit adjustment of the tension to be made after the parts have been assembled.

With these and other objects in view the 30 invention relates to the various elements and combinations of elements hereinafter set forth, the novel features thereof being pointed out in the claims.

In the drawing wherein I have illustrated 35 the invention,

The figure is a view partly in elevation and partly in section of a post insulator embodying the invention.

Referring more particularly to the drawing, I have illustrated a post insulator consisting of a plurality of sections of porcelain or other dielectric material, the sections 1, with the exception of the cap or upper section 2, being substantially identical in 45 construction. Each section 1 is preferably formed as a disk having a central imperforate web 3, a radial outwardly projecting flange 4, and a plurality of hub sections 5 and 6 on opposite sides of the flange 4. The sections 1, while similar in form, are preferably of different diameters. In other words, the hub 6 of the section 2 at the upper portion of the insulator while equal in diameter to the hub 5 of the section immediately below

the same, is of less diameter than the hub 5 of this adjacent section. It is to be understood of course that this change in diameter of the sections is merely a preferred embodiment, and the sections may be of uniform diameter if desired. Each hub section is 60 provided with a flat face to engage the adjacent coacting hub section in order to furnish a uniform bearing around the entire circumference of each hub section. To secure the sections together I provide a plurality of vertical openings 7 in each hub section, and intersecting these openings 7 are a plurality of openings 8, the latter being spaced on opposite sides of the web of each disk. In other words, each opening 8 intersects one of the openings 7, and the openings 8 which intersect the openings 7 formed in one of the hubs 5 or 6, are above or below the web 3 of each section, as the case may be. 70

Seated within the openings 8 and positively maintained in exact position therein are the nuts 9 which are provided with screw threaded openings 10 adapted to receive the correspondingly formed ends of bolts 11. Preferably these nuts are maintained in 80 position by filling the openings 8 with a cementitious compound. At the outer faces of the hub sections and adjacent their point of contact, I provide the base of each opening 7 with an undercut and preferably semi-circular recess 12. These recesses extend inwardly into the hub sections beyond the marginal edge of the opening 7 and are adapted for the reception of nuts 13. The bolts 11 are provided with threaded ends 14 90 adapted to be received within the correspondingly threaded opening in the nuts 13. The nuts 13 and the bolts 11 form in effect turnbuckle means for securely connecting the sections of the insulator. 95

The lowermost section is connected to the base member 15 by means of headed bolts 16, these bolts engaging the nuts 9 which are maintained in the openings 8 in the manner hereinbefore described. The openings 7 in 100 the insulating sections and through the base 15 are of greater diameter than the bolts 11 and 16. This enlargement of the openings in the base member permits the base to expand and contract without causing detrimental strains upon the hub 6 of the adjacent section, while the enlargement of the openings 7 in the intermediate sections are 105

provided to permit a slight flexing of the bolts in order to assemble the same within the nuts 13. The upper section 2, while provided on its under face with a hub 6, is 5 formed on its upper face with a groove 17, a circular flange 18, and an undercut circular groove 19 to provide means for receiving and tying the transmission line to the insulator. The base member 15 is preferably flanged as at 20 and is furnished with 10 a plurality of bolt openings 21 for the bolts 22 which connect the same to the support.

To assemble the device the nuts 9 and bolts 11 are first assembled in each section and 15 then one section is lowered into the other until the adjacent ends of the bolts 11 are seated within the nuts 13, said nuts being preferably provided with right and left hand screw threads whereby movement of 20 the nuts in one direction will force the two adjacent sections into intimate contact, and the rotation of the nuts in the opposite direction will enable the parts to be disassembled.

25 I claim:—

1. In a high tension insulator, a plurality of units of insulating material arranged in superposed relation, each formed at its top and bottom with a cavity and a series of 30 radial openings communicating with the cavity and terminating short of the outer periphery, each unit being further formed with a plurality of openings parallel to the longitudinal axis and communicating with 35 said first named openings, the top and bottom surfaces of the unit being formed with recesses communicating with the second named openings, securing members located within the second named openings and having heads located within the first named 40 openings, and projecting into said recesses, and nut members located within the mating recesses of contiguous units and threaded onto said securing members to act as turn 45 buckles.

2. In a high tension insulator, a plurality of units of insulating material arranged in superposed relation, each formed at its top and bottom with a cavity and a series of 50 radial openings communicating with the cavity and terminating short of the outer

periphery, each unit being further formed with a plurality of openings parallel to the longitudinal axis and communicating with said first named openings, the top and bottom surfaces of the unit being formed with recesses communicating with the second named openings, securing members located within the second named openings and having heads located within the first named 55 openings, and projecting into said recesses, and nut members located within the mating recesses of contiguous units and threaded onto said securing members to act as turn buckles, said radial openings being provided with cementitious material embedding the heads of the securing members. 60

3. In a high tension insulator, a plurality of units arranged in superposed relation and having contacting faces formed with mating 65 recesses, securing bolts arranged in circular series and embedded within the units with their threaded ends projecting into said recesses, and nut members upon said ends of the bolts and located within the mating 70 recesses.

4. A high tension insulator comprising a plurality of units each formed as a body of insulating material, a plurality of turn buckle devices arranged in circumferential series for holding adjacent units in clamping relation, each turn buckle including a pair of bolt elements connected by nut members and terminating in head portions, the units having recesses within which the head portions 80 are engaged. 85

5. In a high tension insulator, a plurality of sections of insulating material of disk form, nuts secured to said sections, and turn-buckle means for engaging the nuts to secure 90 the sections together.

6. In a high tension insulator, a plurality of sections of insulating material of disk form provided with annular concentric hub portions on opposite faces thereof, the hub 95 portions of adjacent sections engaging each other, nuts secured to said sections, and turnbuckle means for securing said sections together.

In testimony whereof I affix my signature.

WALTER T. GODDARD.
